US00D784220S

(12) **United States Design Patent** (10) **Patent No.:** **US D784,220 S**
(45) **Date of Patent:** **** Apr. 18, 2017**

(54) **BRAKE DRUM**

(71) Applicant: **Shandong Haoxin Machinery Co., Ltd.**, Changyi, Shandong Province (CN)

(72) Inventors: **Jixian Lv**, Changyi (CN); **Guangming Pu**, Changyi (CN); **Shiyang Gao**, Changyi (CN); **Shiying Zhu**, Changyi (CN)

(73) Assignee: **SHANDONG HAOXIN MACHINERY CO., LTD.**, Changyi (CN)

(**) Term: **15 Years**

(21) Appl. No.: **29/540,679**

(22) Filed: **Sep. 25, 2015**

(30) **Foreign Application Priority Data**

Aug. 17, 2015 (CN) 2015 3 0308830

(51) **LOC (10) Cl.** **12-16**

(52) **U.S. Cl.**

USPC **D12/179**

CLAIM

The ornamental design for a brake drum, as shown and described.

DESCRIPTION

FIG. 1 is a front view of the brake drum;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is a section view thereof along line 8-8 of FIG. 1.

1 Claim, 8 Drawing Sheets
